UNITED STATES PATENT OFFICE.

JOSIAH DALLAS DORT, OF FLINT, MICHIGAN.

DESIGN FOR A STAND.

SPECIFICATION forming part of Design No. 24,804, dated October 29, 1895.

Application filed December 26, 1894. Serial No. 533,021. Term of patent 7 years.

To all whom it may concern:

Be it known that I, JOSIAH DALLAS DORT, a citizen of the United States, residing at Flint, in the county of Genesee and State of Michigan, have invented and produced a new and original Design for a Stand, of which the following is a specification, reference being had therein to the accompanying drawing.

The invention relates to an original design for a stand, and it is illustrated in the accompanying drawing, wherein the design is shown in perspective.

A is a flat base-piece having the central edge bead B and a depending central post C, from which the legs D project obliquely.

D' represents the flat top.

E are flat uprights extending from the edge

of the top to the edge of the bottom and tapering from the top to the bottom. Between these uprights are uprights formed V shape 20 in cross-section with the apex presented outward. The faces G G' of these uprights are flat and taper from bottom to the top.

The essential feature of the design is the stand, as shown.

What I claim is—

The design for a stand, substantially as shown and described.

In testimony whereof I affix my signature in presence of two witnesses.

JOSIAH DALLAS DORT.

Witnesses:

CHAS. D. WESSON,
FRED A. ALDRICH.
